(57) **CLAIM**

The ornamental design for a gas burner, as shown and described.

DESCRIPTION

FIG. 1 is a top perspective view of a first embodiment of a gas burner;

FIG. 2 is a top perspective view thereof shown in an example environment;

FIG. 3 is a top view thereof shown removed from environment;

FIG. 4 is a bottom view thereof;

FIG. 5 is a side view thereof shown in an example environment;

FIG. 6 is the opposite side view thereof;

FIG. 7 is a front view thereof shown removed from environment;

FIG. 8 is a perspective view of another embodiment of the gas burner showing a series of two gas burners that appear in the first embodiment and in an example environment;

FIG. 9 is a perspective view of another embodiment of the gas burner showing a series of three gas burners that appear in the first embodiment and in an example environment;

FIG. 10 is a perspective view of another embodiment of the gas burner showing a series of four gas burners that appear in the first embodiment and in an example environment;

FIG. 11 is a perspective view of another embodiment of the gas burner showing a series of five gas burners that appear in the first embodiment and in an example environment;

FIG. 12 is a top view of the embodiment shown in FIG. 9;

FIG. 13 is a top view thereof shown in different environment;

FIG. 14 is a bottom thereof shown in different environment;

FIG. 15 is a bottom thereof shown in different environment;

FIG. 16 is a side view cut out as depicted in FIG. 13;

FIG. 17 is a rear view thereof shown in different environment; and,

FIG. 18 is a rear view thereof shown in different environment.

The broken lines showing environment form no part of the claimed design.
